UNITED STATES PATENT OFFICE.

EMANUEL E. NORQUIST, OF KANSAS CITY, MISSOURI.

CONVERTIBLE BODY FOR MOTOR-CARS.

1,266,521.

Specification of Letters Patent. Patented May 14, 1918.

Application filed November 25, 1916. Serial No. 133,821.

To all whom it may concern:

Be it known that I, EMANUEL E. NORQUIST, a citizen of the United States, residing at Kansas City, in the county of Jackson and State of Missouri, have invented certain new and useful Improvements in Convertible Bodies for Motor-Cars, of which the following is a specification.

This invention relates to convertible bodies for motor cars of the Ford runabout type, and has for its object to provide a simple, strong, durable and inexpensive body which, when folded, conforms in appearance to the body of the Ford runabout, and when unfolded constitutes a truck body of good capacity and attractive appearance.

With this object and others in view, as hereinafter appears, the invention consists in the novel construction and combinations of parts, as hereinafter described and claimed; and in order that the invention may be fully understood, reference is to be had to the accompanying drawings, in which:—

Figure 1, is a perspective view of a body embodying the invention, in open or unfolded position.

Fig. 2, is an enlarged central vertical longitudinal section of the body in folded or closed position.

Fig. 3, is an enlarged section taken on the line III—III of Fig. 1.

Fig. 4, is an enlarged fragmentary rear end view with the body in folded position and the end gate depending.

Fig. 5, is a perspective view of a part of the rear member of the body.

Fig. 6, is a central vertical section showing the disposition of the end gate when the body is arranged for general trucking purposes.

Fig. 7, is a fragmentary perspective view with the end gate arranged as a seat.

In the said drawings, 1 indicates the front member of the body, the same on the Ford type of runabout, replacing the box at the rear of the seat, and being contoured at its front end to correspond with and fit against the back wall of the seat and provided with an upright partition 2, dividing the member into a large rear chamber and a small front chamber or pocket, the front and bottom of the latter being formed by the said back wall 3, of the seat, as shown clearly in Fig. 2.

The side walls of said member are provided at their upper margins with out-

wardly-projecting stiffening flanges 4, and the rear end of the bottom is stepped down to provide a transverse recess 5, and is formed with hinge coils or loops 6, for the reception of a transverse hinge rod 7. The rear ends of the side walls are stiffened by vertical reinforce plates 8, welded or otherwise secured at the outer sides of said walls.

The rear member 9, of the body is provided with side walls and a rear end wall, and said walls are stiffened by inwardly-projecting flanges 10, at their upper margins, the side walls being also provided at their lower margins with outwardly-projecting flanges 11. The front end of the rear member is reinforced and strengthened by a U-shaped bar 12, welded or otherwise secured at the inner side of said member.

The rear member is of size to fit snugly within the front member, and when the body is unfolded or open to constitute a truck, the front end of the bottom of the rear member fits in the recess 5, of the front member, as shown clearly in Figs. 1 and 6, the upper surface of the body-portion of the U-shaped bar lying flush with the upper side of the bottom of the front member.

The members are secured operatively together by a pair of pivot bolts 13, extending through the overlapping sides thereof, retaining nuts 14, engaging the inner ends of said bolts, it being understood that said pivot bolts also extend through the stiffening plates 8. As thus connected it is pos-

sible to swing the rear member from the position shown in Fig. 1, to the position shown in Fig. 2, that is to say, by simply swinging the rear member as described, the body is converted into a box conforming in appear-

ance to the box originally a part of the car. By reversing said swinging movement the body becomes a truck of ample capacity for the uses to which Ford cars are usually put, it being noted by reference to Fig. 1, that

the engagement of the front ends of the bottom flanges of the rear member, with the lower edges of the side walls of the front member and the lower ends of the reinforce plates 8, maintains the rear member in proper open relation to the front member.

The rigidity of this relation is increased however, by the abutment of the front end of the bottom and the U-shaped bar against the rear stepped end of the bottom of the front member.

The side portions or arms of the U-shaped

bar 12, are provided with upper and lower bolt holes 15, and corresponding bolt holes 16. Said holes are extended through the side walls of the rear member, the set of holes 15 lying rearward, and the set of holes 16 forward of the vertical plane intersecting the pivot bolts 13. The side walls of the front member are provided with a single set of holes 16^a, for registration with holes 15, 10 when the rear member is in open or unfolded position, and for registration with holes 16, when the rear member is in closed or folded position, and to lock the rear member in either of said positions, a pair of bars 17 are 15 fitted against the plates 8 and provided with bolt-stems 18, extending through holes 16^a, and the set of holes 15 or 16, accordingly as the body is open as a truck or closed as a box. The locking plates 17, are secured in 20 position by nuts 19, engaging the inner ends of the bolt stems 18. It will be understood that the locking plates are employed to secure the convertible body in either of its forms, and that said plates must be removed 25 when it is desired to swing the rear member on its pivots. The plates 17 are offset outwardly as at 20, to accommodate the heads of the pivot bolts, and to guard against accidental displacement thereof.

30 When the body is in folded condition, as shown in Fig. 2, the rear end of the rear member is adjacent the partition 2, and is overlapped by a cover 21, for the pocket hereinbefore identified, said cover serving to 35 prevent water entering the body between the rear member and partition 2. The cover 21 is hinged as at 22, to the upper front corners of the front member, and is offset at 23, to accommodate and overlap the rear member at 40 the front end thereof, when folded upon the front member to constitute a top therefor.

45 Springs 24, one only appearing, connect the cover 21, with the front member and thereby hold said cover down with a yielding force so that it shall not vibrate and produce objectionable noise while the car is in motion. It also serves to prevent movement of the rear member in the event the latter is not locked in folded or closed position by the 50 locking plates, as hereinbefore explained. The cover is provided with a handle 25, for raising it when necessary or desirable, and the member 9, with a handle 26, for convenience in swinging said member.

55 The body is provided with an end gate 27, provided with hinge coils or loops 28, to be aligned with the corresponding parts of the front member and to receive the hinge rod 7, and the lower margin of the end gate is 60 stiffened by a flange 29, which terminates short of the side margins of the gate to produce recesses 30 to accommodate the flanges 10 of the rear member when the gate is used as a seat, as hereinafter explained. Journaled in the end gate is a pin 31, provided

with an operating handle 32 and a latch arm 33. The latch arm is adapted to be engaged with an angle plate 34, on the bottom of the rear member of the body, when the body is unfolded and it is desirable that the 70 end gate shall be out of the way and incapable of swinging. When the body is folded, the end gate is swung upward to close the rear end of the body and is secured in such position by turning the latch arm until it 75 projects through the slot 35, formed in the bar 12 and the bottom of the rear member of the body, as shown in Fig. 2.

To divide the body into a front and rear compartment, the end gate can be fitted in 80 the front member and secured in position by the engagement of the hinge rod with openings 36, formed in the side walls of said member, and should an extra seat be desired, the end gate can be swung from the position 85 shown in Fig. 1, to the position shown in Fig. 7, in which position it rests on the side walls of the rear member, it being noted that it can rest flatly thereon because the recesses receive the upper flanged margins of said 90 walls and the flange 29 of the gate fits between said wall flanges.

From the above description it will be apparent that I have produced a convertible body for motor cars, which possesses the 95 features of advantage enumerated as desirable, and which is susceptible of modification in minor particulars without departing from the spirit and scope of the appended claims.

100 I claim:

1. A convertible body for motor cars, comprising a front member having a vertical cross-partition near its front end, a rear member fitting in and pivoted to the front member for adjustment to form an extension or a top therefor and to be held when arranged as a top, in a downwardly and rearwardly inclined position by the first member, and a hinged cover for the front 110 end of the front member, adapted to overlie the forward end of the rear member when the latter is arranged as a top for the front member.

2. A convertible body for motor cars, comprising a front member having a cross-partition near its front end, a rear member fitting in and pivoted to the front member for adjustment to form an extension or a top therefor, and provided with outwardly-projecting flanges to engage the underside of the front member or the upper side thereof accordingly as said rear member is arranged as an extension or top for the front member, a cover hinged to the front member and adapted for overlapping the rear member when the latter is arranged as a top for the front member, and springs secured to the front member and said cover for holding the latter pressed down upon the rear member. 130

3. A convertible body for motor cars, comprising a front member open at its upperside and rear end and provided with a transverse recess formed by stepping down the rear end 5 of the bottom of the member, a rear member fitting in and pivoted to the front member and adapted to bear along the front edge of its bottom in and against the recessed portion of the front member, and provided with 10 outwardly-projecting flanges to bear against the underside of the sidewalls of the front member when the bottom of said rear member is engaged with said recess of the front member, said flanges being also adapted to 15 rest upon the upper edges of the sidewalls of the front member, when the rear member is swung pivotally over and upon the front member to form a top therefor.

4. A convertible body for motor cars, comprising a front member open at its upperside and rear end and stepped down across the rear end of its bottom, a rear member fitting in the front member and upon the stepped down portion thereof, and provided 25 with outwardly-projecting flanges underlying the sidewalls of said front member, means pivotally connecting the sidewalls of the members together, an end gate hinged to the rear end of the front member and 30 adapted to be swung upward to vertical position to close the rear end thereof when the rear member is swung to a position over the front member, and means to secure the end gate in said last-named position.

5. A convertible body for motor cars, comprising a front member, a rear member fitting in and pivoted to the front member for adjustment to form an extension or top therefor, the rear member having outwardly-projecting flanges to engage the underside of 35 the front member or the upper side thereof accordingly as said rear member is arranged as an extension or top for the front member,

and a part pivoted at its ends to the front member near the upper margin thereof, and 45 adapted to extend downward to form a partition for the body or to extend horizontally rearward and rest on the upper edge of the rear member to constitute a seat.

6. A convertible body for motor cars, comprising a front member, a rear member fitting in and pivoted to the front member for adjustment to form an extension or a top therefor, the rear member having outwardly-projecting flanges to engage the under side 55 of the front member or the upper side thereof accordingly as said rear member is arranged as an extension or top for the front member, and plates fitting against the side walls of the body and each having a plurality of bolts extending through the overlapping walls of the members to secure them 60 against pivotal movement.

7. A convertible body for motor cars, comprising a front member, a rear member fitting in and pivoted to the front member for adjustment to form an extension or a top therefor, the rear member having outwardly-projecting flanges to engage the under side 65 of the front member or the upper side thereof accordingly as said rear member is arranged as an extension or top for the front member, and plates fitting against the side walls of the body and each having a plurality of bolts extending through the overlapping walls of the members to secure them 70 against pivotal movement; said plates being 75 arched over the pivots of the members to prevent outward movement of said pivots.

In testimony whereof, I affix my signature, 80
in the presence of two witnesses.

EMANUEL E. NORQUIST.
